UNITED STATES PATENT OFFICE.

WILLIAM J. PAUL, OF GRAND-VIEW, MANITOBA, CANADA.

PULLING DEVICE.

1,230,211.

Specification of Letters Patent. Patented June 19, 1917.

Application filed January 8, 1917. Serial No. 141,310.

To all whom it may concern:

Be it known that I, WILLIAM J. PAUL, of the town of Grand-View, in the Province of Manitoba, Canada, have invented certain new and useful Improvements in Pulling Devices, of which the following is the specification.

The invention relates to improvements in pulling devices, particularly to an article used for drawing automobiles out of ruts or mires, and the object of the invention is to provide an inexpensive and durable appliance which can be readily set up for work and operated by one person and which will effect, when used, the easy pulling of the stalled automobile.

A further object of the invention is to construct the device so that it can be compactly folded up and stored as part of the regular kit of an automobile and further to arrange it so that when folded it will remain so.

With the above principal objects in view and certain minor objects, which will be more apparent as the description proceeds, the invention consists essentially in the arrangement and construction of parts hereinafter more particularly described and later pointed out in the appended claims, reference being had to the accompanying drawing, in which:—

Figure 1 represents a perspective view of the complete appliance in working position with parts broken away to expose construction.

Fig. 2 represents a plan view of the article folded up.

Fig. 3 represents an enlarged detailed fragmentary sectional view of one of the yoke bars showing the manner in which the operating handle is detachably secured to the same.

Fig. 4 represents an enlarged detailed vertical sectional view through the folded yoke bars showing the manner in which the dog jams them.

Fig. 5 represents an enlarged detailed plan view of the end of one of the spindles with the collar and ring thereon.

In the drawing like characters of reference indicate corresponding parts in the several figures.

The main or frame part of the device is formed from a pair of yoke shaped bars 1 and 2 which bars have their ends formed

into bearings 3, 4, 5 and 6 pivotally mounted on a cross shaft 7 and are provided more or less centrally of their length, one with a swiveled eye 8 and the other with an offset 9. The shaft 7 is supplied at one end with a loop forming a hand grip 10 and carries a split key 11 at the other end which retains the yokes on the shaft.

The yoke bar 2 is slightly smaller than that 1 and according to the construction it is possible to fold this frame with the yoke bar 2 within that 1 in which position the eye enters the offset 9.

12 represents an operating lever having one end plugged with a screw 13, which screw is adapted to screw into the central portion of a third smaller yoke bar 14 which has the ends thereof also formed into bearings 15 and 16 mounted on the shaft and within the bearings 5 and 6.

The arrangement of the yoke bar 14 is such that when the handle is unscrewed the said bar can be folded within the yoke bar 2 and accordingly the device can be folded up to occupy a small space when not in use.

On the shaft and between the ends of the inner yoke bar 14 I mount a drum 17 which has the ends thereof formed to present ratchet wheels 18 and 19.

On the drum I wind a cable 20 which carries a pulley 21 and has the end thereof looped back and tied as shown at 22 to the offset 9.

23 and 24 represent a pair of spring pressed dogs operating on the teeth of the ratchet wheels and slidably mounted on a cross rod 25 extending between the side arms of the yoke bar 14.

A tube 26 is mounted on the rod to space the dogs. Each dog is supplied with an upstanding spindle 27 which passes slidably through the cross portion of the yoke bar 14 and has the upper end thereof fitted with a ring 28.

On the spindles between the dogs and the yoke bar I mount compression springs 29 which operate to continuously press the dogs against the teeth of the wheels.

30 and 31 are similar collars freely mounted on the upper extremities of the spindles and each provided with a pair of opposing slots 32 and 33 which slots in the normal or engaged positions of the dogs are adapted to receive the rings. This latter construction allows me to release and

hold the dogs released from the ratchet teeth by first catching the rings and pulling the spindles out to free the rings from the slots and then afterward turning the collars 5 on the spindles so that the rings ride on the ends of the collars and cannot reenter the slots. The advantage of this will be later apparent.

A gravity dog 34 is pivotally attached 10 at 35 to the bar 2 and has the free end thereof formed into a more or less T-shaped catch 36 adapted to normally play on the teeth of the ratchet wheel 18 and arranged to allow the drum to turn in a left hand direction and prevent the turning of the drum 15 in a right hand direction.

The T-head of the dog (see Fig. 2) extends outwardly over the yoke bar 2 and is fitted with a pair of spaced downwardly 20 extending prong like extensions 37 and 38, the outer one 37 of which is adapted in the folded position of the yoke bars to enter a slot 39 in the bar 1 and the inner one of 25 which is arranged to pass between the yoke bars 2 and 14, these being spaced apart by a washer 40 applied on the shaft 7 between the bearings 6 and 15.

To the eye 8 I connect a chain, rope or such like 41. In order to better understand 30 the invention I will now describe the manner in which it works assuming that it is utilized to pull a stalled automobile out of a rut.

The yokes are opened up from the folded 35 position as shown in Fig. 2 to the open or working position, as shown in Fig. 1, and the chain or cable 41 is attached to any suitable part of the automobile while the pulley of the cable 20 is anchored in a location 40 considerably in advance of the automobile such as by tying it to a stake. The operator then faces the automobile, catches the hand grip 10 in the left hand and the operating handle 12 in the right hand and then 45 ratchets the operating lever forwardly and backwardly. This action causes the drum to be rotated as it is compelled to turn in the backward swinging of the handle by the action of the dogs 23 and 24 and is held 50 locked against turning by the dog 34 in the forward swing of the handle. As the drum rotates the cable 20 will be wound thereon

with the result that the automobile will be pulled out of the rut.

If there is not sufficient slack in the cable 55 20 when one wishes to use the device the drum can be released to turn free by pulling up the spindles and locking them by means of the collars. After the article has been used the handle is unscrewed and the yokes 60 are folded, one inside the other, to occupy the position shown in Fig. 2.

In this form the appliance takes up little room and can be carried as part of the regular equipment. In the folded position it is 65 25 to be noticed that the dog 34 locks in between the yokes, being held by the jamming of the prong like extensions 37 and 38 between the side arms of the yokes.

These extensions serve also to strengthen 70 the dog when it is working as they will act as guides on the side arm of the yoke 2 to prevent any lateral thrust of the dog.

What I claim as my invention is:—

1. In a device of the class described a 75 two part foldable frame, pivots for said parts, a pulling drum carried by said frame, ratchet wheels on said drum, a yoke bar carried by the frame pivots, pawls on said bar co-acting with said ratchets, and means 80 for securing the frame parts and the yoke together.

2. In combination, a two part pivoted foldable frame having cables attached to the opposite ends thereof, a winding drum rotatably mounted in the frame and having one of the cables connected thereto, ratchet wheels at the ends of the drum, a yoke bar spanning the drum and pivotally attached to the frame, spring pressed dogs carried 90 by the yoke bar and engaging the teeth of the ratchet wheels, an operating handle secured to the yoke bar, a dog carried by the frame and engaging one of the ratchet wheels to prevent retrograde turning of the 95 drum and wedge means on one frame part for securing the frame parts and yoke together when in folded position.

Signed at Winnipeg, this 13th day of December, 1916.

WILLIAM J. PAUL.

In the presence of—

G. L. ROXBURGH,

K. B. WAKEFIELD.
